CLAIM

The ornamental design for an icon for timepiece display, as shown and described.

DESCRIPTION

FIG. 1 is a front, isometric view of an icon for a timepiece display showing my new design;

FIG. 2 is a front view of a second embodiment thereof;

FIG. 3 is a front view of a third embodiment thereof;

FIG. 4 is a front view of a fourth embodiment thereof;

FIG. 5 is a front view of a fifth embodiment thereof;

FIG. 6 is a front view of a sixth embodiment thereof;

FIG. 7 is a front view of a seventh embodiment thereof;

FIG. 8 is a front view of a eighth embodiment thereof;

FIG. 9 is a front view of a ninth embodiment thereof;

FIG. 10 is a front view of a tenth embodiment thereof;

FIG. 11 is a front view of an eleventh embodiment thereof; and,

FIG. 12 is a front view of a twelfth embodiment thereof.

The broken line drawing of a timepiece display in all views is for illustrative purposes only and forms no part of the claimed design.
